UNITED STATES PATENT OFFICE

MAX BOCKMÜHL AND GUSTAV EHRHART, OF FRANKFORT-ON-THE-MAIN, GERMANY,
ASSIGNORS TO WINTHROP CHEMICAL COMPANY, INC., OF NEW YORK, N. Y., A COR-
PORATION OF NEW YORK

PROCESS OF PRODUCING TERTIARY NITRILES

No Drawing. Application filed December 4, 1931, Serial No. 579,101, and in Germany December 10, 1930.

The present invention relates to a process of producing tertiary nitriles.

In our U. S. Patent No. 1,690,325, dated November 6, 1928, a process of preparing 5 tertiary nitriles is described which consists in treating a secondary nitrile of the general formula

wherein R stands for alkyl, with an alkali metal or an alkali metal amide and then causing an alkylating agent to act upon the alkali metal compound of the secondary 15 nitrile thus obtained.

Now we have found that the alkali metal compound of secondary nitriles of the general formula

wherein R stands for alkyl or alkenyl, can be obtained with a better yield than according to the said process by causing an organic 25 alkali metal compound of the following formula

wherein R stands for alkyl or aryl and X 30 stands for an alkali metal, to act upon the secondary nitrile.

The new process is, for instance, carried out by dissolving or suspending an organic alkali metal compound in a suitable solvent, e. g. in ether, benzene, ligroine etc., and adding the secondary nitrile to the solutions thus obtained. Hereby a solution of the alkali metal compound of the secondary nitrile is obtained which may then be alkylated according to the known process.

It is not necessary to isolate the organic alkali metal compound before dissolving or suspending it in a solvent. The process may advantageously be carried out by preparing 45 the organic alkali metal compound in the same solution to which the secondary nitrile is to be added. For instance, sodium ethyl may be prepared from sodium and mercury diethyl in ether, or sodium phenyl may be prepared from sodium and chlorobenzene in

benzene, and to the solutions thus obtained the secondary nitrile may be added.

The secondary nitrile may be added after preparing the organic alkali metal compound or it may be present during its formation. The solutions of the alkali metal compounds of the secondary nitriles thus obtained may preferably be used immediately for the alkylation process; the alkylating agent, as for instance, an alkyl halide, may be added to the solutions whereby the alkylation takes place.

The tertiary nitriles can be prepared according to the present process with a better yield than according to the known process, 65 as the alkali metal compounds of the secondary nitriles which are to be alkylated are now obtained with a better yield than by causing the alkali metal itself to act upon the secondary nitrile. For instance, according to the process of our U. S. Patent No. 1,690,325 a yield of only about 35% of the theoretical weight of diethylaceto-nitrile-sodium is obtained when causing sodium to act upon diethylacetonitrile; therefore, when 70 alkylating the product thus obtained, not more than 35% of alkyl diethylacetonitrile 75 can be obtained. But now according to the new process yields up to 90% of the theoretical weight can be obtained.

The following examples illustrate our invention.

(1) 2.5 grams of sodium in the form of wire are covered with 150 cc. of dry ether and 15 grams of diethyl mercury are added 85 drop by drop. Then 11.3 grams of diethylacetonitrile are added drop by drop, whereupon a very lively reaction sets in. After an hour's stirring 8.3 grams of allyl chloride are added drop by drop, the very lively reaction being moderated by cooling. The reaction product is poured into ice water and the ethereal extract is separated first from the mercury precipitated and then from the aqueous portion and dried. After having 90 distilled off the ether, the residue is fractionated in a vacuum, whereupon the diethylallyl acetonitrile is obtained which melts at 71° C. to 74° C. under 14 mm. pressure.

(2) 11.5 grams of sodium (in the form of 100

wire) are covered with 100 cc. of benzene and 23 grams of butylchloride are introduced, drop by drop, at 0° C. to 5° C. in a nitrogen atmosphere. After the course of 4 to 5 hours 5 nearly all of the sodium is consumed. 24 grams of diethylacetonitrile are then introduced drop by drop, at 0° C.-10° C. After introduction of the whole quantity and stirring for 1 hour at room temperature, 19 10 grams of allyl chloride are introduced drop by drop, while strongly cooling. The whole is finally boiled for 1/2 hour in a reflux apparatus. The reaction product is poured into water, the aqueous portion is separated and 15 again extracted with ether. The ethereal extract is combined with the benzene extract and dried; the ether and benzene are distilled off and the residue is distilled in a vacuum. Diethylallylacetonitrile is obtained; it boils 20 at 79° C. to 81° C. under 20 mm. pressure.

(3) On 11.5 grams of sodium (in the form of wire) there are poured 125 cc. of benzene and 28 grams of chlorobenzene are added. The reaction sets in after about 1/2 hour, but 25 the temperature must preferably not exceed 30° C. As soon as the reaction is complete, 24 grams of diethylacetonitrile are introduced drop by drop, but the temperature must preferably not be above 20° C. to 30° 30 C. After introduction of the whole quantity and stirring for 1 hour at room temperature, 18 grams of allyl chloride are added while strongly cooling. After the product has been worked up as described in Example 2, 31 35 grams of diethylallylacetonitrile are obtained.

(4) 16 grams of sodium and 41 grams of chlorobenzene are caused to react in a mixture of 100 cc. of benzene and 100 cc. of ligroin 40 in (boiling at 50° C. to 80° C.) as described in Example 3. 30 grams of diallylacetonitrile are then introduced, drop by drop, while cooling. The whole is preferably stirred for 1 hour. Then 26.5 grams of isoamyl chloride 45 are introduced. The product is worked up as indicated in Example 3. 38 grams of diallylisooamylacetonitrile are obtained. It boils at 109° C. to 110° C. under 7 mm. pressure.

(5) 11.5 grams of sodium and 30 grams of chlorobenzene are caused to react in 120 cc. of benzene as described in Example 3 and mixed first with 21 grams of ethylallylacetonitrile and then with 14.5 grams of allyl chloride. 21 grams of ethyldiallylacetonitrile 50 are obtained; it boils at 83° C. to 85° C. under 13 mm. pressure.

(6) 11.5 grams of sodium and 30 grams of chlorobenzene are caused to react in 120 cc. 55 of benzene as described in Example 3 and mixed in succession with 25 grams of butyl-ethylacetonitrile and 15.5 grams of allyl chloride. 28 grams of ethyl-butyl-allylacetonitrile are obtained; it boils at 75° C. to 77° C. 60 under 2 to 3 mm. pressure.

(7) 16.0 grams of sodium and 41 grams of chlorobenzene are caused to react in a mixture of 100 cc. of benzene and 100 cc. of ligroin (boiling at 50° C. to 80° C.) as described in Example 3 and mixed in succession with 34 70 grams of diallylacetonitrile and 21.5 grams of allyl chloride. 40 grams of triallylacetonitrile are obtained. It boils at 86° C. to 88° C. under 8 to 9 mm. pressure.

(8) 46 grams of sodium, 400 cc. of dry benzene and 120 grams of chlorobenzene are mixed together and stirred with exclusion of atmospheric moisture and carbonic acid. As soon as the reaction sets in, 75 grams of diethylacetonitrile are added drop by drop and the temperature is raised to at most 25° C. When the reaction is complete, the whole is stirred for 4 to 6 hours at room temperature and 59 grams of allyl chloride are then introduced, drop by drop, while cooling. Finally the whole is heated for 1/2 hour to 60° C. it is then poured into water, separated and the aqueous portion is again shaken with benzene; the benzene solution is washed with water, dried by way of sodium sulfate, the benzene is distilled off and the residue is distilled in a vacuum. The diethylallylacetonitrile distills over at 76° C. to 78° C. under 14 mm. pressure. The yield amounts to 90 grams.

(9) 46 grams of sodium are covered with 400 cc. of benzene and a mixture of 120 grams of chlorobenzene and 75 grams of diethylacetonitrile is introduced, drop by drop, the whole being cooled in such a manner that the reaction temperature does not exceed 20° to 25° C. After the reaction is complete, the whole is stirred for 4 to 5 hours and 59 grams of allyl chloride are introduced, drop by drop, while cooling. The product is worked up as indicated in Example 8. 90 grams of diethylallylacetonitrile are obtained.

(10) 11.5 grams of sodium are covered with 120 cc. of benzene and a mixture of 30 grams of chlorobenzene and 21 grams of ethylallylacetonitrile is introduced by drops, the whole being cooled in such a manner that the temperature does not exceed 20° C. to 25° C. The whole is then stirred for 4 to 5 hours and 14.5 grams of allyl chloride are introduced by drops. After having worked up the product as indicated in Example 8, there are obtained 25 grams of ethyldiallylacetonitrile. It boils at 83° C. to 85° C. under 13 mm. pressure.

(11) 16 grams of sodium are covered with 100 cc. of benzene as described in Example 10 and a mixture of 34 grams of diallylacetonitrile and 41 grams of chlorobenzene is run in. The whole is then mixed with 21.5 grams of allyl chloride. The product is worked up as indicated in Example 8. 41 grams of triallylacetonitrile are obtained; it boils at 86° C. to 88° C. under 8 to 9 mm. pressure.

(12) 11.5 grams of sodium, 120 cc. of benzene, 29 grams of chlorobenzene and 18 grams 130

of diethylacetonitrile are mixed together and stirred. The very lively reaction which sets in after a short time is moderated by cooling.

After 2 to 3 hours 14 grams of allyl chloride 5 are introduced by drops and the whole is worked as indicated in Example 8. 16 grams of diethylallylacetonitrile are obtained.

(13) 11.5 grams of sodium, 120 cc. of benzene and 18 grams of diethylacetonitrile are 10 mixed and 29 grams of chlorobenzene are introduced at 20° C. to 30° C. into the mixture. After the reaction is complete, 14.5 grams of allyl chloride are introduced by drops while cooling. After having worked up as indicated in Example 8, 20 grams of diethylallyl-acetonitrile are obtained.

In the following claims the step of causing 20 to act an organic alkali metal compound upon the secondary nitrile is equivalent to the step which consists in forming the organic alkali metal compound in the presence of the secondary nitrile.

We claim:

1. In the process of preparing tertiary nitriles by transforming a secondary nitrile of 25 the general formula

wherein R stands for alkyl or alkenyl, into 30 the corresponding alkali metal compound and causing an alkylating agent to act upon the alkali metal compound of the secondary nitrile, the step which comprises preparing the alkali metal compound of the secondary nitrile by causing an organic alkali metal compound of the general formula

wherein R stands for alkyl or aryl and X stands for an alkali metal, to act in the presence of a solvent upon the secondary nitrile.

2. In the process of preparing tertiary nitriles by transforming a secondary nitrile 45 of the general formula

wherein R stands for alkyl or alkenyl, into 50 the corresponding alkali metal compound and causing an alkylating agent to act upon the alkali metal compound of the secondary nitrile, the step which comprises preparing the alkali metal compound of the secondary nitrile by causing an organic alkali metal compound of the general formula

wherein R stands for ethyl or phenyl and X stands for an alkali metal to act in the presence of an organic solvent upon the secondary 65 nitrile.

3. In the process of preparing tertiary nitriles by transforming a secondary nitrile of the general formula

70

wherein R stands for alkyl or alkenyl into 75 the corresponding sodium compound and causing an alkylating agent to act upon the sodium compound of the secondary nitrile, the step which comprises preparing the sodium compound of the secondary nitrile by causing sodium phenyl to act in the presence of an organic solvent upon the secondary nitrile.

4. In the process of preparing tertiary nitriles by transforming a secondary nitrile of the general formula

85

wherein R stands for alkyl or alkenyl into 90 the corresponding sodium compound and causing an alkylating agent to act upon the sodium compound of the secondary nitrile, the step which comprises preparing the sodium compound of the secondary nitrile by causing sodium phenyl to act in the presence of benzene upon the secondary nitrile.

5. In the process of preparing tertiary nitriles by transforming the secondary nitrile 95 of the formula

100

into the corresponding sodium compound and causing an alkylating agent to act upon the sodium compound of the secondary nitrile, 105 the step which comprises preparing the sodium compound of the secondary nitrile by causing sodium phenyl to act in the presence of benzene upon the secondary nitrile.

In testimony whereof, we affix our signatures.
